VENTILATOR

Filed Oct. 1, 1925

Patented Apr. 17, 1928.

UNITED STATES PATENT OFFICE.

ANDREW L. RIKER, OF FAIRFIELD, CONNECTICUT.

VENTILATOR.

Application filed October 1, 1925. Serial No. 59,891.

This invention relates to a ventilator useful for many purposes, but designed to be more especially useful in connection with a blower or exhaust fan as now commonly employed in building structures.

When special ventilating apparatus adapted to force air into or exhaust air from a structure is utilized, there must be an opening in the structure through which the air can pass. When the ventilating apparatus is inoperative, it may be desirable under some circumstances to have the opening closed.

An object of the present invention is to provide a ventilator adapted in wide open position to present a minimum amount of resistance to the passage of air through the ventilator, as when air is being forced into or exhausted from a structure, and adapted in closed position to effectively and positively close all spaces within the ventilator, as when a special ventilating apparatus associated with the ventilator is inoperative and it is desirable that the ventilator be closed.

A further object is to provide a ventilator of practical, durable, and economic construction which will include novel characteristics and features of construction that are improvements generally over ventilators heretofore known.

A further object is to provide a ventilator including a frame consisting of plates, louvers pivoted in the frame, some of the plates having inwardly extending flanges at their side edges adapted to interlap with certain louvers pivoted in the frame, and one of the plates being designed to support the operating mechanism of the ventilator and to also interlap with a pivoted louver, the louvers and frame plates being situated relatively to each other so that when the operating mechanism is manipulated to move the louvers to closed position, all of the spaces of the ventilator between adjacent louvers and between the louvers and the frame, are effectively and positively closed.

A further object is to provide a ventilator as just stated, wherein there is a minimum amount of resistance to the passage of air through the ventilator when the louvers are in wide open position.

A further object is to provide a ventilator including oppositely disposed plates, and louvers having their opposite ends mounted

in the plates, the plates having offset portions near the louver pivots adapting each plate to be drawn in toward the louver ends to be closely adjacent to, or contiguous with, said louver ends when the louvers are in closed position, to thus preclude the passage of air between the ends of the pivoted louvers and the plates having the louver pivots.

And a still further object is to provide in the ventilator a simple and improved construction of operating mechanism including an operating bar having its end portion bent to general U-shape, a spindle mounted in one of the plates of the ventilator and including a crank and a manipulating handle, the U-shaped portion of the operating bar receiving the crank, and novel mechanism fixing the U-shaped portion of the operating bar and the spindle relatively to each other and precluding the possibility of misshaping 75 of the U-shaped portion or the possibility of the U-shaped portion having movement relatively to the remainder of the operating bar.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and meant in no way in a limiting sense, changes in details of construction and arrangement of parts being permissible so long as within the spirit of 90 the invention and the scope of the appended claims.

In the accompanying drawing forming a part of this specification,

Fig. 1 is an elevational view of the improved ventilator as seen from the left in Fig. 3, disclosing the louvers in closed position and the manipulating handle removed;

Fig. 2 is a sectional view on line 2-2 in Fig. 1, disclosing the louvers in open position;

Fig. 3 is a sectional view corresponding with the showing of Fig. 2, the louvers being closed;

Fig. 4 is an enlarged fragmentary sectional view corresponding with the disclosure of the lower portion of Fig. 2;

Fig. 5 is a sectional view on line 5-5 in Fig. 4;

Fig. 6 is an enlarged sectional view as on

line 6—6 in Fig. 1, the louvers being in open position;

Fig. 7 is an enlarged sectional view as on line 7—7 in Fig. 1, an intermediate part of the ventilator being broken away;

Fig. 8 is a detail perspective view of the keeper and key for the U-shaped portion of the operating bar; and

Fig. 9 is an enlarged sectional view on line 9—9 in Fig. 1.

The ventilator of this invention is constituted by a frame of rectangular configuration, spaced apart louvers pivotally mounted in the frame, and mechanism for swinging the louvers on their pivots to open or close the space within the frame.

The frame may be composed of sheet metal, and may consist of oppositely disposed plates or members, denoted 10 and 11, having inwardly extending flanges, denoted 12 and 13, respectively, a similar plate or member 14, with inwardly extending flanges 15, between the plates 10 and 11, and a plate or member 16, opposite the plate 14 and between said plates 10 and 11, this latter plate 16 including an intermediate portion 17 which is, as disclosed, disposed to be almost horizontal when the ventilator is in use, and also including outwardly extending, spaced apart, parallel flanges 18, 19, for a purpose to be explained, the flange 19 terminating at its lower portion in an oblique flange 20, extending outwardly of the ventilator and away from the flange 18, which oblique flange 20 terminates in a flange 21 extending outwardly of the ventilator and parallel with the flanges 18 and 19. All of the flanges 12, 13 and 15 are, desirably, perpendicular to the plate bodies 16 with which they are integral, and when the frame members are assembled the flanges 18, 21 are adapted to fit against the flanges 12, 13, as are also the flanges 15.

The manner in which the members 10, 11, 14 and 16 are preferably joined is best shown in Figs. 2, 3 and 9, wherein an end portion of member 14 and its flanges 15 is disclosed as fitted within flanges 12 of plate 10, the connection between the member 14 and the member 10 being made by means of a rivet 22 passing through the flanges 12 and 15, a bushing 23 extending between the flanges 15 and through which the rivet passes, serving to allow the rivet to clamp the flanges 12 and 15 against each other. Similarly, the member 11 is connected with the member 14, as are both members 10 and 11 with the member 16. In the case of the member 16, the rivets 22 pass through the flanges 18, 21 and 12 or 13, as the case may be, while the bushings upon said rivets extend between the flanges 18 and 21.

The ventilator includes a plurality of spaced apart louvers 24 pivotally mounted therein, all of the louvers being preferably

composed of sheet metal. As disclosed, the louvers are mounted in the frame to be perpendicular to the members 10 and 11 and parallel with the members 14 and 16.

The louvers are spaced at equal distances apart. Each is a flat strip of metal having a stiffening rib 25 upon one of its side edges, and each flat strip has ears 26, 27, upon its opposite ends and pivoted to the plates 10 and 11, respectively. The ears 26 and 27 preferably extend at right-angles in the same direction from the plane of each louver strip. Each ear 26 has an extension 28 projecting beyond the pivot for the ear upon the plate 10, which extension is for a purpose to be explained.

The louvers are mounted in the members 10 and 11 in the manner best shown in Fig. 7. Each ear 26 and 27 is drawn as at 29 to rotatably enter an annular flange 30 consisting of inwardly drawn metal of the plate or member 10 or 11, as the case may be. Eyelets 31 insure the assembled relation of the ears and annular flanges.

Numeral 32 represents an operating bar for manipulating the louvers. The operating bar is arranged beneath the extensions 28 of the ears 26 to slide upon the plate 10 of the frame, and each of the extensions 28 has metal drawn therefrom and rotatably entering holes 33 at uniform distances apart in the operating bar.

The mechanism for moving the operating bar longitudinally to turn the louvers on their pivots in a manner which will be obvious, consists of a spindle 34 mounted in the flanges 18, 19 of the member 16, adjacent a corner of the ventilator, and having a crank 35 and a manipulating handle 36. Adjacent one of its ends the operating bar is bent to general U-shape, as denoted at 37, to receive the crank.

The metal of the flanges 18, 19, may be drawn as denoted at 38 to provide a dependable bearing for the spindle 34, and the U-shaped part of the operating bar is preferably arranged about the crank so that the slight forward and rearward movements of the operating bar when moved longitudinally to adjust the louvers impart slight end-wise movements to the spindle. Evidently, the operating bar thus insures the spindle against longitudinal displacement from its bearings.

The position of the U-shaped portion of the operating bar upon the spindle and the position of the end of the bar, denoted 39, beyond the spindle, is insured by a keeper 40 having an opening 41 at its center and flanges 42, 43 upon its opposite ends, the opening 41 being adapted to receive the U-shaped portion 37, the flange 42 being adapted to engage the adjacent face of the body of the operating bar adjacent the spindle, as indicated at 44, 130

and the flange 43 being adapted to engage the adjacent face of the end 39 beyond the spindle, while spaced apart surfaces 45, 46, of the face of the keeper opposite the flanges 5 42 and 43 engage, respectively, enlarged cylindrical surfaces, denoted 47 and 48, adjacent opposite ends of the crank 35. Numeral 49 indicates a key upon the operating bar 32, between the flange 42 and the U-shaped portion of the bar, and beneath the body of the keeper, engaged by said keeper, said flange 42, and said U-shaped portion, the key having flanges 50 upon its opposite ends which are bent about the side edges of said operating bar. See Figs. 5 and 8. Clearly, the key insures the set position of the keeper, and the keeper, in turn, insures the set relation of the spindle and its crank with respect to the U-shaped portion of the operating bar, and also insures that there can be no misshapement of said U-shaped portion and that there can be no relative movement between the U-shaped portion and the remainder of the operating bar.

The throw of the crank 35 determines the distance the operating bar can move longitudinally, and hence limits the degree to which the louvers can be turned on their pivots. In Fig. 2 the louvers are in open position, so that each louver is parallel with the plate or member 16. In Fig. 3 the louvers are closed. Here the edge of each louver opposite its stiffening rib 25 engages the edge of an adjacent louver at said stiffening rib, while the top outermost louver shown interlaps with a flange 15 of the member 14, and the bottom outermost louver interlaps with the flange 19 of the member 16.

By drawing the metal of the frame member 10 inwardly to form the annular flanges 30, I provide a space 51 between the extensions 28 of the ears 26 and the frame member 10 to afford clearance for the longitudinal sliding movements of the operating bar upon said frame member 10. This will be clear from Fig. 7. Also, by drawing the metal of both frame members 10 and 11 inwardly to form the annular flanges 30 adapted to nicely receive the drawn portions of the ears 26 and 27, I cause the louver ends to be spaced a slight distance from the parts of the plates having the pivots carrying said louver ends. The spaces between the louver ends and the plates or members 10 and 11 need not be considered when the louvers are in open position, but when the louvers are closed, their ends should be closely adjacent to, or contiguous with, said plates or members 10 and 11. To the accomplishment of this desirable feature, I offset each plate 10, 11, inwardly for its full length, as indicated at 52, at a location adjacent the louver pivots, the inwardly set portions 53 of the plates being those in proximity to the louvers when closed, so that in the closed

position of the louvers their ends come close to, or in contact with, the plates (see Fig. 7) to thus preclude the passage of air between the ends of the pivoted louvers and the plates having the louver pivots.

It will be noted that the spindle 34 and its appurtenances are at the side of the portion 17 of the member 16 opposite the louvers, so that said member 16 is required to be cut away, as at 54, to allow passage of the operating bar 32. Also, the flanges 12 are cut away as at 55 to clear the spindle 34. See Fig. 1.

As will be evident, when the louvers are in closed position, there is an effective and positive closing of all of the spaces of the frame, between the louvers and the frame, as well as between adjacent louvers.

The present ventilator has been constructed with the idea in view of providing a structure designed to shed dirt and dust, special attention being here called to the fact that no part of the ventilator includes a pocket or cavity in which dirt and dust can accumulate, the frame member 16 of the ventilator having flat surfaces all of which are readily and easily accessible to be wiped with a rag or the like.

Having thus fully described the invention, what I claim as new and desire to secure by Letters Patent is:

1. As an article of manufacture, a device comprising a rectangular frame consisting of joined metallic plates, opposite plates having flanges upon their opposite edges extending inwardly beyond the body of the frame, a plate between the opposite plates having flanges upon its opposite edges extending inwardly beyond the body of the frame, a plate between said opposite plates mentioned and having flanges extending outwardly of the frame, louvers pivotally mounted in said opposite plates between the inwardly extending flanges thereof, the other plates being adapted to cooperate with the louvers when swung to closed position to close the spaces in the frame, and means mounted in said outwardly extending flanges for manipulating said louvers.

2. As an article of manufacture, a device comprising a rectangular frame consisting of joined metallic plates, opposite plates having flanges upon their opposite edges extending inwardly beyond the body of the frame, a plate between the opposite plates having flanges upon its opposite edges extending inwardly beyond the body of the frame, a plate between said opposite plates mentioned and having flanges extending outwardly of the frame, louvers pivotally mounted in said opposite plates between the inwardly extending flanges thereof, the other plates being adapted to cooperate with the louvers when swung to closed position to close the spaces in the frame, and the op-

posite plates having inwardly set portions adapted to be arranged approximately contiguous with the louver ends when the louvers are in closed position.

3. As an article of manufacture, a device comprising a rectangular frame consisting of joined metallic channel pieces, opposite channel pieces having their marginal portions extending inwardly of the frame, a channel piece between said opposite channel pieces and having its marginal portions extending inwardly of the frame, a channel piece between said opposite channel pieces mentioned and having its marginal portions extending outwardly of the frame, and louvers pivotally mounted in said opposite channel pieces first mentioned and between the other channel pieces, said louvers being adapted to be swung to open position to allow passages through the frame and to closed position to close all of said passages, and said opposite channel pieces mentioned having inwardly set portions arranged in close proximity to the louver ends when the louvers are in closed position.
4. In a device of the character described, a frame plate and a louver having an ear pivoted on said plate, the plate including an annular flange, the ear having drawn metal entering the annular flange, and the frame plate having an inwardly set portion adjacent the louver pivot adapted to be situated contiguous with an end of said louver.
5. In a device of the character described, a frame plate, and spaced apart louvers each having an ear pivoted to said plate, the plate including spaced apart annular flanges, each ear having drawn metal entering a flange, and the frame plate being set inwardly adjacent all of said annular flanges to be situated approximately contiguous with an end of each louver.
6. In a device of the character described, a plate, a louver having an ear pivotally supported upon said plate and spaced therefrom, an operating bar pivotally associated with said ear and arranged beneath the

same between the ear and plate, a crank with handle operatively associated with said bar, a portion of the bar being bent to general U-shape about the crank, and means for insuring the position of the bar about the crank, the means including a keeper with opening receiving the U-shaped portion of the bar, the keeper engaging a spindle carrying said crank and also engaging the operating bar at a location at each of said U-shaped portion.

7. In a device of the character described, a plate, a louver having an ear pivotally supported upon said plate and spaced therefrom, an operating bar pivotally associated with said ear and arranged beneath the same between the ear and plate, a crank with handle operatively associated with said bar, a portion of the bar being bent to general U-shape about the crank, and means for insuring the position of the bar about the crank, the means including a keeper with opening receiving the U-shaped portion of the bar, the keeper being situated between a spindle having said crank and the operating bar, spaced surfaces of a face of said keeper engaging said spindle, and flanges upon said keeper engaging the body of said operating bar at one side of said U-shaped portion and the end of said bar at the other side of said U-shaped portion.

8. The combination as specified in claim 7, and a key insuring the set relation of said keeper with respect to the operating bar and spindle.

9. The combination as specified in claim 7, and a key insuring the set relation of said keeper with respect to the operating bar and spindle, the key being disposed between the operating bar, the U-shaped portion thereof, the keeper, and one of the keeper flanges, and having end flanges bent about the side edges of the operating bar.

Signed at Bridgeport, in the county of Fairfield, and State of Connecticut, this 29th day of September, A. D. 1925.

ANDREW L. RIKER.
